UNITED STATES PATENT OFFICE.

WILLIAM DALY, OF NEAR JOHANNESBURG, SOUTH AFRICAN REPUBLIC.

MACHINE FOR FORGING AND SHARPENING ROCK-DRILLS.

SPECIFICATION forming part of Letters Patent No. 631,281, dated August 22, 1899.

Application filed June 8, 1899. Serial No. 719,832. (No model.)

To all whom it may concern:

Be it known that I, WILLIAM DALY, a subject of the Queen of Great Britain and Ireland, and a resident at the Robinson Gold Mining Company, Limited, near Johannesburg, in the South African Republic, have invented certain new and useful Improvements in and Relating to Machines for Forging and Sharpening Rock-Drills and the Like, of which the following is a specification.

This invention relates to an improved machine for forging and sharpening rock-drills and tools of a similar nature, particularly those drills having more than one cutting edge, such as three-winged or "star" bits.

My invention consists of a series of rapidly-reciprocating hammers, the direction of their blows converging toward the center, which beat the shank of the drill-bit into shape, the sharpening being performed by a rapidly-reciprocating horizontally-moving hammer which carries a cress or die shaped according to the drill which it is intended to produce.

My invention will be fully described with the aid of the accompanying drawings, in which—

Figure 1 shows a sectional elevation; Fig. 2, a plan view, partly sectional; Fig. 3, an end elevation of my machine with front plate H removed.

A is a horizontal shaft provided with a fly-wheel or fly-wheels A' and having a driving-pulley A² keyed thereto by which motion is imparted to the machine, said shaft A being supported in bearings B formed in the framework of the machine. The center of the shaft is eccentrically turned, as at C, imparting a backward-and-forward motion to the block C', the end of which bears against the main horizontally-sliding block D, which is recessed at D² to receive the end thrust of the block C'. The block D slides horizontally between guides D' D', bolted to the framework of the machine, and is caused to reciprocate through a short distance—say one-eighth of an inch—by means of the eccentric C, the recoil-springs E E forcing the block D backward and keeping it always pressed against the eccentric-block C'. The block D is formed on its front face with a central boss recessed or machined to receive the shank of the particular sharp-

ening-die F which it is intended to employ. The construction of the said die-block F will vary with the end of the drill which it is intended to sharpen—*e. g.*, if a star-bit, the die-block F will be formed on its face with a cress in the shape of a cross, which will correspond with the cross-sectional form of the drill. The slide-block D also imparts motion to the series of hammers G which slide in guides G', formed in the front circular casting H', which is bolted to the framework of the machine. The hammers G are set so that the direction of their blows converge toward the center, the hammer-heads being constructed according to the nature of the drill-bit which it is desired to produce. In the accompanying drawings four such hammers are shown shaped at either end so that the resulting drill-bit will be of the class known as "star-bits." Each of the hammers G moves toward the center simultaneously, motion being imparted thereto by the toggle-links K K'. The sliding block D is provided with recesses or pads L, into which the ends of the toggle-links K are adapted to be received, the ends of the toggle-links K' being received into recesses or pads formed in the blocks L', fixed to the framework H'. The other ends, respectively, of the toggle-links K K' are adapted to be received into recesses formed in the block M, the lower end of which projects and is received into a recess M', formed in the sliding hammer-block G. Each of the hammers G is furnished with tension-springs G², which give the hammer-blocks G their backward motion and keep the toggle-links K K' always tight in their respective recesses or seatings, so that there is no lost motion. In this manner the movement of the horizontal sliding block D forward also causes the hammers G G to converge, the springs E E and G² G² reversing the direction of the various parts. Thus the forming-hammers G G and the sharpening-hammer F all move simultaneously.

A cutting device is adapted to the machine immediately in front of the forming-hammers G G for the purpose of cutting broken or misshapen drills before sharpening. This cutting device consists of cutters N N', bolted to blocks N' N', which slide in the same guides

G' G' as the hammer-blocks G G, being placed immediately in front of same. The sliding hammer-blocks G are furnished with front projecting pieces G³ and the cutter-blocks N', formed with a corresponding recess, so that the inward motion of the hammers G is at the same time imparted to the cutter-blocks N'. O O are wedge-shaped blocks, the inclines of which bear, respectively, upon the bottom of the projections G³ and the tops of the recesses, so that as the wedges O are moved into position the cutter-blocks N' are moved forward a corresponding amount, and vice versa. O' O² are recesses or grooves formed on either flat face of each of the wedge-shaped blocks O, and the inner faces of the hammer-blocks G and the cutter-blocks N' are respectively machined to fit into said recesses O' O². By this construction the various parts are held together. There are as many cutters attached to blocks N' as there are hammers G. Thus if there are four hammers G as shown in the drawings there will be four cutting-blocks N' and four wedges O to operate same. Each of the wedges O is connected to a circular plate P by means of connecting-links P' P'. The plate P is adapted to be received into a recess formed in the front casting of the machine and is retained in position by the studs P². On turning the plate P from right to left by means of the handle P³ the wedges O are moved forward, thereby compressing the cutter-blocks N' and causing the points of the cutters N to converge. By turning the plate P in the opposite direction the wedges O return to their normal position, drawing the cutter-blocks N' back with them, so as to be inoperative.

In order to determine the size of the drills, there are four expanding-jaws T, which move in slides T', formed in the front circular casting II'. These jaws T move simultaneously inwardly and outwardly, as the case may be, as hereinafter described, and bear upon the webs 45 of the drill, and thus regulate the size of the drill. The jaws T T are moved by wedges T², the inclines of which bear upon the upper ends 50 of the jaws T, said wedges being recessed or dovetailed, as shown in Fig. 3, into the sliding jaws T. The wedges T² are driven in or out by means of a circular plate V, provided with a number of inclines V² on its circumference—one for each wedge. Thus as the machine in the drawings is adapted for sharpening stars-bits there will be four jaws T, and consequently four operating-wedges T² and four circumferential inclines on the circular plate V. On turning the circular plate V by means of the handle V' in one direction the circumferential inclines will force the wedges T² forward, thus causing the jaws T to be simultaneously moved toward one another. The ends of the wedges are furnished with projections T³, which fit into a corresponding groove formed on the inner face of the circular plate V, so as to bring back the wedges. When the circular plate

V is turned in the other direction, the jaws T T are carried back with the wedges by means of the dovetails aforementioned.

An index may be provided against the circular plate V, so that it may be instantly set at any desired position, according to the particular size of the drill-bit which it is intended to produce.

In order to hold the drills while the sharpening operation is being performed, a horizontal table is adapted to the front of the machine, being securely bolted thereto. The top of this table R slides horizontally toward the front of the machine, being traversed by a screw or worm R', which is carried in the bearings R², formed in the ends of the table. This screw or worm R' actuates an internal screw-nut or boss R³, which is secured to the under side of the sliding top R of the table. Motion is imparted to the said screw worm or thread through the crown-wheels R⁴ R⁴, actuated through the handle R⁵, situated at the side of the machine, so that in this manner the top of the table may be brought to any desired distance from the front of the machine. The top of the table is provided with a series of stops S S, which are constructed in the form of plungers sliding vertically in recesses or sockets S' S', formed in the sliding top R of the table. These stops or plungers S S are furnished with light springs S² S² beneath them, so as to be depressed into their respective sockets or recesses S' S' when the weight of the drill is laid upon them. The first of the series S therefore, which is so far along the table R as not to be depressed by the drill, takes the end thrust of the drill while the process of sharpening is being performed, any intermediate adjustment which may be necessary being accomplished by giving the handle R⁵ operating the screw-worm R' a few turns. By this construction all lengths of drills may be dealt with without altering the machine in any way.

Having now described my invention, what I claim as new, and desire to secure by Letters Patent, is—

1. An improved drill-sharpening and forging machine comprising the framework H', the horizontally-sliding block carrying a sharpening-die with means for operating said block, the hammers movable radially in guides in said framework, springs tending normally to force said hammers outward, inclined toggle-arms K' seated between said hammers and the framework and toggle-arms K between the sliding block and hammers, substantially as described.

2. An improved drill-sharpening and forging machine consisting in combination of a rotatory shaft A provided with an eccentrically-moving member operating a horizontal sliding block D provided with a sharpening-die F formed with a cress to sharpen the particular shape of bit required, the series of forming-hammers sliding in guides G' formed in the circular front plate and work-

ing toward a common center and adapted to form the shank of the bit operated from the main sliding block D through the toggle-links K K', the tension-springs E E and G² G² for maintaining the aforementioned parts in their relative positions, the cutters N operated from the sliding hammers G and controlled by the wedges O connected through the links P' to an adjustable annular plate, the adjustable jaws T to determine the size of the web of the drill working in guides T' formed in the front of the circular plate V provided with circumferential inclines and the holding device consisting of a table adapted to the front of the machine having a sliding top R regulated and controlled by the screw-worm R' and furnished with the spring-stops S, substantially as hereinbefore described and illustrated on the accompanying drawings.

3. An improved device for taking the longitudinal thrust of a drill while it is being sharpened consisting of a table having a sliding top controlled by a screw-worm so that it may be brought forward or backward as required, and provided with a series of spring-stops (such as S S) which are depressed when the drill is laid upon the table so that the strain of the drill is taken by the next stop beyond the end of the drill, substantially as hereinbefore described and illustrated on the accompanying drawings.

In witness whereof I have hereunto set my hand in presence of two witnesses.

WILLIAM DALY.
